17 Claims. (Cl. 230—138)

1

This invention relates to rotary screw pumps and motors of the type comprising intermeshing, helically ribbed rotors which are adapted for transporting or compressing fluids, especially air and other gases, or for operation as expandable fluid engines, and is more particularly directed to the improved forms of such apparatus disclosed in my copending applications, Serial No. 511,083, filed November 20, 1943, and Serial No. 707,384, filed November 2, 1946, now Patents Nos. 2,460,310 and 2,511,878, dated February 1, 1949, and June 20, 1950, respectively.

Although the devices of these prior applications and those of the present invention are reversible in operation so as to function as either pumps or motors, the following description will, in the interest of simplicity, designate the devices as pumps and use phraseology generally applicable to air compressors. By so doing, however, it is not intended to limit the scope of the invention to pumps or compressors, although it is in this field that it would appear to find its greatest utility at the present time.

The pumps disclosed in the above identified applications, upon which the present invention is an improvement, are characterized by the combination of a pair of coacting rotors, each having a single helical rib or thread, which rotate in intermeshed relation in a casing continuously open at the inlet end to a source of low pressure fluid and having intermittent connection at the other end with a high pressure or discharge conduit, and means for controlling communication between the discharge conduit and the fluid transporting and compressing space defined by the rotor ribs in such a manner that the fluid is confined in said space until the desired pressure is built up, whereupon, once in every revolution of the rotors, the space is opened to the discharge conduit through a passageway or port which faces, and lies within the axially projected cross section of, the threaded portion of one of the rotors. The latter rotor may conveniently be called the discharge or driving rotor, while the other is known as the mating or driven rotor.

In the first of the earlier filed applications, the discharge of the fluid from the compression space is controlled by a valvular device comprising two apertured coacting valve elements, one being fixed to the casing and the other being connected to the discharge rotor and turning therewith to open the high pressure end of said rotor to the discharge conduit once in each rotation. In the second application, the escape of the fluid into the discharge conduit is controlled by a fixed

2

discharge port of predetermined configuration and volumetric capacity which is opened and closed periodically by the rotation of the discharge rotor itself, the end of the rotor rib or thread serving to cover and uncover the port as the rotor turns.

Both of these prior pumps are capable of maintaining a constant flow of gas or other fluid into the discharge line at a predetermined pressure without objectionable surging or other variable pressure conditions in the fluid at the discharge end of the pump. While it is possible to vary the compression ratio of these prior devices by changing the size and configuration of either the 10 passageway in the rotating valve element of the first application or the discharge port in the second application, it is necessary to stop the pump and take it out of service for this purpose, since the change involves replacement of either 15 the rotating valve element or that in which the discharge port is formed.

It is therefore the principal object of the present invention to provide, in a device of the class described, novel means for varying the compression ratio which can be actuated, either manually or automatically, while the device is in operation.

Another object is to provide a pump of the 20 rotary screw type with improved means for controlling the point in the cycle of the device at which the high pressure end of the compression space defined by the rotors is opened to communication with the discharge line, which means permit variation of the time of fluid discharge 25 without the necessity for an interchange of parts or removal of the device from service.

A further object is to provide a screw type gas 30 pump or compressor having a built-in compression ratio which may be varied over a substantial range without varying the efficiency of the device, and wherein the output pressure is determined by the circumferential or angular position of a discharge port of fixed size and shape which is rotatably adjustable about the axis of the discharge rotor of the pump.

Still another object is to provide a compressor 35 of the character described with means for preventing a further build-up of pressure therewith during each cycle after the discharge port has once been opened and closed, particularly when said port is so positioned as to provide a relatively low compression ratio.

These and other objects will appear more fully upon consideration of the detailed description of 40 certain embodiments of the invention which fol-

lows. Although only two specific forms of apparatus are described and illustrated in the accompanying drawings, it is to be expressly understood that these drawings are for the purpose of illustration only and are not to be construed as defining the scope of the invention, for which latter purpose reference should be had to the appended claims.

Referring now to the drawings, wherein like reference characters indicate like parts throughout the several views:

Fig. 1 is a plan view of one form of screw pump or compressor embodying the invention with certain parts shown in section, the section being taken substantially on the line 1—1 in Fig. 2;

Fig. 2 is a side elevation of the device shown in Fig. 1 with certain parts shown in section, the section being taken substantially on the line 2—2 in Fig. 1;

Fig. 3 is a cross section of the same construction taken substantially on the line 3—3 in Fig. 2, looking inwardly toward the high pressure or discharge ends of the rotors and showing the adjustable discharge port in the position which produces the maximum discharge pressure and compression ratio;

Fig. 4 is a cross sectional view similar to Fig. 3, but wherein the discharge port is so positioned as to produce a lower discharge pressure than in the case of Fig. 3;

Fig. 5 is a cross sectional view of the device of Figs. 1 and 2 taken substantially on the line 5—5 in Fig. 1 but turned through 90° for easier comparison with Figs. 3 and 4, this view looking in the opposite direction to Figs. 3 and 4 showing the position of the relief passageway which prevents an excessive build-up of pressure when the discharge port is so located as to provide a relatively low compression ratio, as in the case of Fig. 4;

Figs. 6, 7, 8, 9 and 10 are views similar to Figs. 1, 2, 3, 4 and 5, respectively, of a second embodiment of the invention.

Referring now to Figs. 1—5, the pump structure shown therein comprises a horizontally extending casing 21 open at both ends and having a laterally projecting fluid intake conduit 22 adjacent one end and, adjacent the other end, a similar fluid discharge conduit 23. As shown best in Fig. 5, the main body of the casing 21 is 8-shaped in cross section, consisting of a pair of hollow cylinders 24 and 25 in partially overlapped relation with their axes parallel and offset from one another, the discharge end of the casing being enlarged as indicated in Figs. 3 and 4 to form a substantially elliptical fluid discharge chamber 26. The open ends of the casing 21 are normally closed by a pair of hollow heads 27 and 28 which are removably secured to the flanged ends of the casing in any suitable manner, as by bolts (not shown). Housed in each of the casing heads 27 and 28 are a pair of combination radial and end thrust bearings 29 which rotatably support the shafts 30 and 31 of a pair of intermeshed, helically threaded rotors 32 and 33 adapted, in known manner, to transport air, gas or other fluid from the intake conduit 22, through the casing 21 and out through the discharge conduit 23, and at the same time to compress the fluid prior to discharge.

The shaft 30 of the rotor 32, hereinafter referred to as the driving or discharge rotor, projects outwardly of the casing head 27 at the intake end of the casing, and is adapted to be connected to a suitable source of power for turning

the driving rotor in the direction indicated by the arrows appearing at the right of Figs. 1 and 2. The shaft 31 of the second rotor 33, hereinafter referred to as the driven or mating rotor, is drivably connected to the shaft 30 of the driving rotor by means of gears 34 housed in the casing head 27 which are adapted to rotate both screws at the same speed.

The rotors 32 and 33 are keyed to their respective shafts 30 and 31 for rotation therewith, and are held against axial movement along said shafts, to the right as viewed in Figs. 1 and 2, by stop shoulders 35 and 36 formed on the shafts. The driving rotor 32 is provided with a single helical thread or rib 37 having at least one full turn or convolution, the peripheral surface of which has a running fit in the upper portion of the casing 21 formed by the cylinder 24. The driven rotor 33 is similarly provided with a thread or rib 38 of the same length as the thread 37 and having a running fit in the lower cylinder 25 of the casing.

As shown best in Fig. 2, each of the threads or ribs 37 and 38 is concave in longitudinal cross section at one side, while the opposite side is convex. For example, the left side 39 of the driving thread 37 is concave, as viewed in Fig. 2, while the right side 40 is convex, or substantially so. The driven thread 38 is oppositely formed in that its left side 41 is convex, or practically convex, while the right side 42 is concave. The result is that the two rotors are so formed that the similarly shaped sides of the threads face one another, and that the concave side 39 of the driving thread 37 of the discharge rotor faces the fluid discharge chamber 26. It will also be noted that, in this preferred form of rotor construction, which is the subject matter of the previously mentioned Patent No. 2,511,873, the thread 37 of the discharge rotor is relatively thin in an axial direction in comparison with the thread 38 of the driven rotor, and that the groove 43 between the turns of the thread 37 is correspondingly wider than the groove 44 of the driven rotor.

By reference to Fig. 5, it will be seen that each rotor exhibits in any section perpendicular to its axis a compound curved outline consisting of an outer peripheral surface 45 of cylindrical curvature conforming to the curvature of the inside wall of the casing in which it rotates, an inner root or dedendum circle 46 concentric with the associated rotor shaft, a concave side 47 connecting one end of the outer peripheral surface 45 and one end of the exposed portion of the root circle 46, and a convex side 48 connecting the other end of the peripheral surface with the root circle. The concave side 47 of the thread is of epicycloidal shape, while the convex side 48 has a curvature substantially that of an Archimedean spiral.

The stop shoulders 35 and 36 on the rotor shafts are located, as shown in Figs. 1 and 2, a substantial distance inwardly of the casing from the casing head 27 so as to provide a relatively large fluid intake chamber 49 which is in permanently open, direct communication with the fluid intake conduit 22 and also communicates with the intake end of the fluid transporting and compressing space 50 defined by the rotor threads 37 and 38 and the surrounding wall of the casing 21. In order to control the discharge of the fluid which is picked up by the screws from the intake chamber 49 and transported axially through the casing 21, the discharge end of the latter is provided with a novel arrangement of elements which per-

mits the fluid to be discharged from the space 50 into the discharge chamber 26 and conduit 23 once in every revolution of the rotors, and also permits the time of said discharge to be varied with respect to the angular positions of the rotors without dismantling the pump or even stopping its operation.

In the embodiment illustrated, there are removably fitted into the discharge end of the casing 21 two hollow castings 51 and 52 having outer walls 53 and 54, respectively, which abut casing head 28, and inwardly extending sleeves or bosses 55 and 56 through which pass the rotor shafts 32 and 33, respectively. The inner end of the sleeve 55 of the upper casting 51 is reduced in diameter at 57 to provide a bearing for a rotatably adjustable valve member 58 in which is formed a discharge or cut-off port 59 adapted to register once in each revolution of the rotors with another port 60 formed in a disc 61 which is fixed to and rotates with the driving rotor shaft 30. When the ports 59 and 60 overlap, the fluid in the space 50 can escape into the channel 62 formed by the hollow interiors of castings 51 and 52 and thence into the discharge chamber 26 and outlet 23. When the ports 59 and 60 are not in registry, the fluid is retained in the space 50 and is compressed in a manner hereinafter described.

The valve member 58 has a central hub 63 which is journaled on the reduced diameter portion 57 of sleeve 55, an annular web or body portion 64 in which the cut-off port 59 is located, and an outer rim portion 65 which is provided with gear teeth 66 on its outer periphery for the purpose of rotatably adjusting the valve member about the axis of the driving rotor shaft 30 so as to vary the circumferential position of the port 59. In the embodiment illustrated, the gear teeth 66 extend around the entire rim 65 in the form of a worm wheel and are in engagement with a worm 67 which is fixed to a shaft 68 journaled in and extending laterally outwardly of the enlarged elliptical portion of the casing 21 surrounding the discharge chamber 26. The outer end of the worm shaft 68 is provided with a suitable handwheel 69 or other means for rotating the worm and thereby adjusting the valve member. The inner vertical surface of the web or body portion 64 of the cut-off valve member 58 abuts the outer or left-hand surface of the disc valve 61 as viewed in Figs. 1 and 2, and is held thereagainst both by the shoulder 70 on the sleeve 55 of casting 51 which abuts the outer end of the hub 63 and by the pressure of the fluid in the discharge chamber 26 and the communicating channel 62. The rim 65 of the valve member is recessed as indicated at 71 to receive a ring 72, L-shaped in cross section, which engages the left-hand end of the portion of the casing 21 formed by the upper cylinder 24 and the upper arcuate edge 73 of the inner vertical wall 74 of casting 52, and which assists in properly positioning and centering the valve member.

The inner vertical wall 74 of the lower casting 52 abuts the discharge end of the thread 38 of the driven rotor 33 and forms an imperforate barrier to the escape of fluid into the channel 62 and discharge chamber 26 from that portion of the fluid transporting and compressing space 50 which is defined by the unmeshed portion of the driven rotor thread 38 and the lower portion of the casing 21, i. e., that portion of the driven rotor groove 44 which is un-

occupied by the driving rotor thread 37. The cut-off valve member 58, which is substantially coextensive in cross-sectional area with the axially projected area of the driving rotor thread 37, similarly blocks the escape of fluid from the upper portion of the space 50 at all times other than when the port 60 of the disc valve 61 registers with the cut-off port 59 in the valve member 58. The length of time during which the fluid may be discharged from the space 50 depends upon the size and configuration of the coacting ports 59 and 60, while the point in the cycle of operation of the pump at which this discharge occurs is determined by the angular position of the cut-off port 59 about the axis of the driving rotor shaft 30.

Referring now to Figs. 3-5, the cut-off port 59 therein shown extends over approximately one-quarter of the area of the web or body portion 64 of valve member 58, and is bounded by two concentric arcs *a*-*b* and *c*-*d* of different radii having the axis of the driving rotor shaft as their center, and by two other arcs *a*-*c* and *b*-*d* having the same radius as the rotors. The circumferential or angular length of the port 59, which is approximately 90° in the construction illustrated, determined the limits between which the compression ratio of the pump may be varied by adjustment of the port about the axis of the driving rotor. The position of the cut-off port 59 shown in Fig. 3 represents one extreme of its adjustability, the position in which the compression ratio is a maximum (approximately 4 to 1 in the present instance). In this maximum pressure position, the left-hand end of the cut-off port 59 defined by the arc *a*-*c* is substantially parallel to the upper left-hand portion of the periphery of the driven rotor. By rotating the valve member 58 in a clockwise direction as viewed in Fig. 3, by means of the handwheel 69, worm shaft 68 and worm 67, the position of the cut-off port 59 may be varied so as to permit discharge of the compressed fluid from the rotors at an earlier point in the cycle of operation, and thereby produce a lower final pressure and compression ratio. For example, when the cut-off port 59 occupies the position shown in Fig. 4, representing the opposite limit of its adjustability in the structure illustrated, the compression ratio is reduced to about 2 to 1. If desired, suitable stops may be provided to prevent the valve member 58 from being rotated beyond the intended limits of its movement represented by the positions of the port 59 shown in Figs. 3 and 4.

As will be apparent from Figs. 3 and 4 which show the two extreme positions to which port 59 may be adjusted, said port always lies wholly within the axially projected outline or area of that portion of the driving rotor thread 37 which is out of mesh with the driven rotor thread 38; i. e., it never lies within the axially projected outline or area of the intermeshing portions of the rotor threads represented by the lens shaped area below the shaft 30 enclosed within the lines 45 and 73 in Fig. 5.

In the embodiment of the invention illustrated, the port 60 formed in valve disc 61 is lens shaped and is of the maximum permissible area, this area being equal to the axially projected area of the intermeshing portions of the rotor threads. Although the disc port 60 can be reduced below this maximum size, in which event it is possible to lengthen the cut-off port 59 in a clockwise direction as viewed in Figs. 3 and 4 and thereby

attain a lower minimum pressure, it cannot be made larger without resulting in a "leak-through" from the high pressure side to the low pressure side of the pump.

Because of the fixed circumferential or arcuate length of the cut-off port 59, whenever the latter is in any position other than that illustrated in Fig. 3 (wherein the maximum compression ratio is provided) the discharge of fluid from the space 50 is cut off, due to rotation of the disc port 60 out of registry with the cut-off port, prior to completion of the rotational cycle of the pump. For example, when the cut-off port 59 is in the minimum compression position shown in Fig. 4, a wedge-shaped pocket having a projected area $a-c-e-f$ is formed between the concave leading side 39 of the driving thread 37 and the barrier formed by the imperforate portion of the web 64 of the valve member 58, which pocket has a zero thickness along the line $a-c$ and a maximum thickness along the line $e-f$, the latter thickness depending on the helix angle of the thread. As the screws continue to rotate, the volume of this pocket approaches zero with a consequent increase in pressure of the fluid trapped therein. In order to save power and prevent possible damage to the apparatus, means are provided for relieving the fluid pressure which would thus be built up in this pocket by venting the fluid directly into the discharge chamber 26 or the discharge conduit 23. In the embodiment of the invention illustrated, this is accomplished by providing a suitably dimensioned by-pass opening 75 through the wall of the casing 24 closely adjacent the discharge or high pressure end thereof and leading into the discharge conduit 23, said opening being located in the portion of the casing formed by the upper cylinder 24 just above the intersection of the latter with the lower cylinder 25, as shown in Fig. 5. With this construction, the fluid remaining in the pocket $a-c-e-f$ after the discharge path through the disc port 60 and cut-off port 59 has been closed is by-passed into the discharge conduit without affecting the efficiency of the pump in any manner.

The method of operation of the device disclosed in Figs. 1-5 is the same in principle as that of the apparatus of the above identified Patent No. 2,460,310, the principal difference being that, in the pump of the present invention, the compression ratio may be varied, within the limits permitted by the size and shape of the cut-off port 59, by simply rotating the valve member 58 and thereby adjusting the position of the cut-off port about the axis of the driving rotor. Assuming that air is supplied to the intake conduit 22 and that the rotors 32 and 33 are being driven from a suitable source of power connected to the driving rotor shaft 39, the air entering the intake chamber 49 will flow into the low pressure or right-hand ends of the rotor grooves 43 and 44 and will be advanced by the rotor threads 37 and 38 toward the left as viewed in Figs. 1 and 2. As the rotors turn, the transporting and compressing space 50 formed by the grooves 43 and 44 gradually decreases in volume so that the air trapped therein between the advancing rotor threads and the barrier formed by the valve member 58 and the inner vertical wall 74 of the casting 52 is placed under pressure. Since the discharge end of the driven rotor groove 44 is always cut off from direct communication with the discharge chamber 26 by the wall 74, the air compressed in

50

55

60

65

70

75

79

80

this groove is transferred to the portion of compression space 50 formed by the driving rotor groove 43 for final compression and discharge. The discharge or cut-off port 59 is so positioned that the disc port 60 comes into registry therewith just as the rotors have advanced to the point where the air is compressed to the desired degree, whereupon continued rotation of the rotors and disc valve 61, with the ports 59 and 60 in direct communication with one another, causes the air to flow out of the compression space 50, through the channel 62 and discharge chamber 26 into the discharge conduit or outlet 23. If it is desired to vary the discharge pressure produced by the pump, it is only necessary to adjust the position of the cut-off port 59 by means of the handwheel 69. When the cut-off port 59 is in any position other than that which provides the maximum discharge pressure obtainable (Fig. 3), the by-pass opening 75 serves as a relief port for preventing the production of an undesired pressure in the terminal or discharge end of the driving rotor groove 43 after communication between the cut-off port 59 and disc port 60 has been shut off.

Referring now to Figs. 6-10, the pump structure illustrated therein is of substantially the same construction as that of Figs. 1-5 except for omission of the disc valve 61 and its port 60 and a change in the configuration of the discharge or cut-off port which is designated by the reference numeral 59' in Figs. 6-10. Omission of the disc valve also results in a reduction in the thickness of the inner vertical wall 74 of the lower casting 52, since said wall no longer has to provide a bearing surface for the disc valve as in the previously described embodiment. Inasmuch as the common features of the two structures will be apparent from the drawings, it is unnecessary to describe in detail those portions of Figs. 6-10 which find their counterparts in Figs. 1-5.

The discharge or cut-off port 59' of Figs. 6-10 differs from the corresponding element of the first embodiment only in the shape of the curve which defines the right-hand end of the port as viewed in Figs. 8 and 9. Instead of being a circular arc of the same radius as the rotors, this curve $b-d'$ is of the same shape as the convex edges of the rotor threads when viewed in axial cross section as shown in Fig. 10, i. e., a close approximation of an Archimedean spiral. With a cut-off port of this configuration and of the angular length shown in the drawing, a maximum compression ratio of approximately 2 to 1 is obtained with the port in the position shown in Fig. 8. In Fig. 9, the port is so positioned as to provide a 1 to 1 compression ratio, in which event the device functions merely as a fluid transport apparatus, rather than a compressor. It will be understood, particularly by reference to the disclosure of the above mentioned Patent No. 2,511,878, which is directed to the same basic structure as that embodied in Figs. 6-10 hereof, that higher compression ratios may be obtained by shortening the angular length of the port 59' and thereby reducing both the area of the port and the length of time during which the compressed fluid may be discharged from the compression space into the discharge chamber and conduit constituting the compressor outlet.

The operation of the embodiment of Figs. 6-10 is substantially the same as that of the previously described device of Figs. 1-6, except that opening and closing of the cut-off port 59' is controlled directly by the end of the driving rotor thread 37, instead of by the disc valve 61 and port 60.

There are thus provided by the present invention improved forms of screw type pumps or compressors wherein the compression ratio or discharge pressure produced by the device may be readily controlled and varied during operation by a simple adjustment of the position of a discharge or cut-off port of predetermined size and shape, and wherein provision has also been made for relieving any undesired pressure that may be built within the pump following delivery of a charge of the desired pressure when the cut-off port is so positioned as to provide a compression ratio less than the maximum attainable.

While two specifically different devices embodying the invention have been described and illustrated in the accompanying drawings, it will be obvious that the invention is not limited to the particular structures shown, but is capable of a variety of mechanical embodiments. For example, although the means for rotatably adjusting the valve member carrying the discharge or cut-off port have been shown as a manually operated worm and worm wheel arrangement, it is obvious that other forms of actuating mechanism, such as a rack and pinion, bevel gears or the like, may be substituted for the specific arrangement illustrated, and that the adjustment may be made automatically as well as manually, as by the use of any suitable pressure responsive actuator to which the output pressure of the pump, or any other desired pressure, might be applied as the controlling medium. It should also be apparent that, since the cut-off port valve member need have only a limited rotational movement, it is unnecessary that the gear teeth extend completely around the periphery thereof, although such an arrangement is advantageous in that it permits location of the worm or equivalent driving element at a number of different positions around the casing. The intake and discharge conduits likewise may be located at various points about the casing different from the laterally projecting positions illustrated in the drawings. It is also to be understood, as previously pointed out, that while the above description has been directed primarily to pumps and compressors of the positive displacement type, the same structures may be used as rotary engines of the expansible fluid type by simply reversing the direction of flow of the fluid therethrough.

Various other changes, which will now become apparent to those skilled in the art, may be made in the form, details of construction and arrangement of parts of the herein disclosed devices without departing from the inventive concept. Reference is therefore to be had to the appended claims for a definition of the limits of the invention.

What is claimed is:

1. In a rotary screw type pump or motor embodying a pair of helically ribbed rotors adapted to rotate in intermeshed relation in a casing continuously open at one end to a conduit in which a relatively low fluid pressure prevails and having restricted communication at the other end with a conduit wherein a higher fluid pressure exists, means for controlling communication between the high pressure conduit and the high pressure end of the fluid compression or expansion space defined by the rotor ribs and the casing comprising a member normally fixed with respect to said casing forming an imperforate wall perpendicular to the axis of said rotors which prevents direct flow of fluid between the high pressure end of one of said rotors and the high

wall-forming portion complementary to the wall formed by said first member and facing the high pressure end of the second rotor, said second member being rotatably adjustable relatively to said casing and to said second rotor about the axis of the latter, a single port in the wall-forming portion of said second member having continuous communication with the high pressure conduit and communicating with the high pressure end of said second rotor during at least a portion of each revolution of the latter, and means for rotatably adjusting said second member about the axis of said second rotor to vary the circumferential position of said port.

2. In a rotary screw type pump or motor embodying a pair of helically ribbed rotors adapted to rotate in intermeshed relation in a casing continuously open at one end to a conduit in which a relatively low fluid pressure prevails and having restricted communication at the other end with a conduit wherein a higher fluid pressure exists, means for controlling communication between the high pressure conduit and the high pressure end of the fluid compression or expansion space defined by the rotor ribs and the casing comprising a member normally fixed with respect to said casing forming an imperforate wall perpendicular to the axis of said rotors which prevents direct flow of fluid between the high pressure end of one of said rotors and the high pressure conduit, a second member having an annular wall-forming portion complementary to the wall formed by said first member and substantially coextensive in area with the axially projected area of the ribbed portion of the second rotor, said second member being rotatably adjustable relatively to said casing and to said second rotor about the axis of the latter, a single port in the wall-forming portion of said second member having continuous communication with the high pressure conduit and communicating with the high pressure end of said second rotor during at least a portion of each revolution of the latter, and means operable from outside said casing for rotatably adjusting said second member about the axis of said second rotor to vary the circumferential position of said port.

3. In a rotary screw type pump or motor embodying a pair of helically ribbed and grooved rotors adapted to rotate in intermeshed relation in a casing continuously open at one end to a conduit in which a relatively low fluid pressure prevails and having restricted communication at the other end with a conduit wherein a higher fluid pressure exists, means for controlling communication between the high pressure conduit and the high pressure end of the fluid compression or expansion space formed by the rotor grooves comprising a member normally fixed with respect to said casing forming an imperforate wall perpendicular to the axis of said rotors which prevents direct flow of fluid between the high pressure end of the groove of one of said rotors and the high pressure conduit, a second member having a wall-forming portion complementary to the wall formed by said first member and facing the high pressure end of the second rotor, said member being rotatably adjustable relative to said casing and to said second rotor about the axis of the latter, a single port in the wall-forming portion of said second member opposite the unmeshed ribbed portion of said second rotor, means providing direct communication at all times between said port and the high pressure conduit, means for establishing communication

between said port and the high pressure end of the groove of said second rotor for a limited time during each revolution of the latter, and means operable during rotation of said rotors for rotatably adjusting said second member about the axis of said second rotor to vary the circumferential position of said port.

4. A screw type fluid pump comprising a pair of intermeshing, helically threaded rotors, a casing for said rotors having a fluid inlet adjacent one end and a fluid outlet adjacent the other end, said fluid inlet being in direct communication with the intake end of the fluid pumping space defined by the rotor threads and the casing, and means for providing restricted communication between the discharge end of said fluid pumping space and the fluid outlet from said casing including a partition perpendicular to the axes of said rotors at the discharge end of said fluid pumping space, one portion of said partition being normally fixed relative to the casing and forming an imperforate barrier to the direct discharge of fluid to the fluid outlet from the portion of said fluid pumping space defined by the unmeshed portion of the thread of one of said rotors, another portion of said partition being movable about the axis of said second rotor, a single port in the movable portion of said partition lying wholly within the axially projected outline of the unmeshed threaded portion of said second rotor, said port having direct communication with the fluid outlet and communicating with the discharge end of the fluid pumping space during at least a portion of each rotation of said rotors, and means for moving the said movable portion of the partition about the axis of said second rotor to vary the circumferential position of said port.

5. A screw type fluid pump comprising a pair of intermeshing, helically threaded and grooved rotors, a casing for said rotors having a fluid inlet adjacent one end and a fluid discharge chamber at the other end, said fluid inlet being in direct communication with the intake end of the fluid pumping space formed by the rotor grooves, and means for providing restricted communication between the discharge end of said fluid pumping space and the fluid discharge chamber including a partition in said discharge chamber perpendicular to the axes of said rotors at the discharge end of said fluid pumping space, one portion of said partition being normally fixed to the casing and another portion being movable about the axis of one of said rotors, the fixed portion of said partition having an imperforate wall abutting the discharge end of the second rotor and having an area substantially equal to the axially projected area of the unmeshed threaded portion of said second rotor, whereby direct discharge of fluid from the groove of said rotor into the discharge chamber is prevented, the movable portion of said partition facing the discharge end of the first rotor and having an area substantially equal to the axially projected area of the entire threaded portion thereof, a single port in the movable portion of said partition lying wholly within the axially projected outline of the unmeshed threaded portion of said first rotor, said port having direct communication with the fluid discharge chamber and communicating with the discharge end of the groove in said first rotor during at least a portion of each rotation of said rotors, and means for moving the said movable portion of the partition

about the axis of said first rotor to vary the circumferential position of said port.

6. A screw type fluid pump comprising a pair of intermeshing, helically threaded rotors, a casing for said rotors having a fluid inlet adjacent one end and a fluid outlet adjacent the other end, said fluid inlet being in direct communication with the intake end of the fluid pumping space defined by the rotor threads and the casing, and means for providing restricted communication between the discharge end of said fluid pumping space and the fluid outlet from said casing including a partition perpendicular to the axes of said rotors at the discharge end of said fluid pumping space, one portion of said partition being normally fixed to the casing and another portion being movable about the axis of one of said rotors, a single port in the movable portion of said partition lying wholly within the axially projected outline of the unmeshed threaded portion of said last named rotor and having direct communication with the fluid outlet, the remainder of said partition being imperforate, means for establishing communication between the discharge end of the fluid pumping space and said port once during each rotation of said rotors comprising an apertured disc fixed to said last named rotor at the discharge end thereof and abutting the movable portion of said partition, and means for moving the movable portion of the partition about the axis of said last named rotor during rotation of the rotors to vary the circumferential position of said port.

7. A screw type fluid pump comprising a pair of intermeshing, helically threaded and grooved rotors, a casing for said rotors having a fluid inlet adjacent one end and a fluid outlet adjacent the other end, said fluid inlet being in direct communication with the intake end of the fluid pumping space formed by the rotor grooves, and means for providing restricted communication between the discharge end of said fluid pumping space and the fluid outlet from said casing including a partition perpendicular to the axes of said rotors and in abutting engagement with the discharge ends thereof, one portion of said partition being normally fixed to the casing and another portion being movable about the axis of one of said rotors, a single port in the movable portion of said partition lying wholly within the axially projected outline of the unmeshed threaded portion of said last named rotor and having direct communication at all times with the fluid outlet, the remainder of said partition being imperforate, said port having communication with the discharge end of the groove of said last named rotor whenever said port is uncovered by the end of the thread of said last named rotor, and means for moving the movable portion of the partition about the axis of said last named rotor during rotation of the rotors to vary the circumferential position of said port.

8. A rotary screw type pump according to claim 4 wherein the means for moving the movable portion of the partition to vary the position of the port includes an actuating member operable from outside the casing of the pump.

9. A rotary screw type pump according to claim 4 wherein variation in the position of the port in the movable portion of the partition varies the compression ratio of the pump, and which includes a relief passageway leading from a point in the fluid pumping space closely adja-

cent the partition to the fluid outlet for venting fluid from said space to the outlet when said port is in any position other than that wherein the maximum compression ratio is obtained.

10. A rotary screw type pump according to claim 4 wherein the pump casing is formed by a pair of overlapping cylinders producing a casing substantially 8-shaped in cross section, and which includes a relief passageway through the casing wall at a point closely adjacent the partition and the plane of intersection of said overlapping cylinders, said passageway connecting the fluid pumping space in the casing with the fluid outlet so as to by-pass fluid from said space to the outlet.

11. A rotary screw type pump according to claim 6 wherein the sides of the port in the movable portion of said partition are defined by a pair of circular arcs of different radii concentric with the axis of the rotor about which the port is movable, while the ends of the port are concave and are defined by a second pair of circular arcs of the same radius as said rotor.

12. A rotary screw type pump according to claim 7 wherein the sides of the port in the movable portion of said partition are defined by a pair of circular arcs of different radii concentric with the axis of the rotor about which the port is movable, one end of the port is concave and is defined by a circular arc of the same radius as said rotor, while the other end is convex and is approximately an Archimedean spiral in shape.

13. In a screw compressor having a casing and a pair of helically threaded screws adapted to rotate in intermeshed relation with a running fit in said casing and to compress a fluid during its passage through the casing prior to discharge therefrom, means for controlling the discharge of the compressed fluid from the casing comprising a wall across the discharge end of the casing including two coating elements having a combined area perpendicular to the axes of the screws equal to the cross-sectional area of the threaded portions of said screws, one of said elements being annular in form and substantially coextensive in area with the axially projected outline of the threaded portion of one of said screws, means for supporting said element for rotational movement about the axis of said screw and in close proximity to the discharge end thereof, the second element being normally fixed relative to the casing and forming an imperforate barrier abutting the discharge end of the second screw except for the area thereof which meshes with the first named screw, a single discharge port formed in said movable element through which the compressed fluid is discharged from the casing during at least a portion of each revolution of the screws, and means operable from outside the compressor casing for rotatably adjusting said movable element about the axis of said first named screw to vary the circumferential position of said port and thereby vary the pressure of the fluid discharged therethrough.

14. A screw compressor comprising a casing,

a pair of helically threaded rotors adapted to rotate in intermeshed relation with a running fit in said casing and to compress a fluid during its passage through the casing prior to discharge therefrom, each of said rotors having a thread which is concave on one side and convex on the other side, said rotors being so intermeshed that the concave side of the thread of the first rotor faces the concave side of the thread of the second rotor and also faces the discharge end of the casing, and means for controlling the discharge of the compressed fluid from the casing including a wall across the discharge end of the casing perpendicular to the axes of said rotors, the portion of said wall facing the discharge end of said first rotor being movable about the axis of said rotor, the remainder of said wall being fixed relative to the casing and forming an imperforate barrier to the discharge of fluid from the casing, 15 a single discharge port formed in the movable portion of said partition and lying wholly within the axially projected outline of the unmoved portion of the thread of said first rotor, and means for rotatably adjusting said movable portion of the partition about the axis of said first rotor to vary the circumferential position of said port and thereby vary the pressure of the fluid discharged therethrough.

15. A screw compressor according to claim 14 wherein the movable portion of the partition is annular in form and substantially coextensive in area with the axially projected outline of the threaded portion of said first rotor.

16. A screw compressor according to claim 14 30 wherein communication between the fluid compression space within the casing and said discharge port is controlled by an apertured disc to said first rotor at the discharge end thereof and abutting the movable portion of said partition.

17. A screw compressor according to claim 14 35 wherein the discharge end of the thread of said first rotor abuts the movable portion of said partition and controls communication between the fluid compression space within the casing and said discharge port.

GILBERT RATHMAN.
